COIN-TESTING MECHANISM FOR COIN-CONTROLLED VENDING-MACHINES.

1,180,713.

Specification of Letters Patent. Patented Apr. 25, 1916.

Application filed April 22, 1913. Serial No. 762,810.

To all whom it may concern:

Be it known that we, ALBERT D. GROVER and EARL E. BARBER, citizens of the United States, and residents, respectively, of 5 Malden, in the county of Middlesex, State of Massachusetts, and Boston, county of Suffolk, State of Massachusetts, have invented certain new and useful Improvements in Coin-Testing Mechanisms for Coin-10 Controlled Vending-Machines, of which the following is a specification.

Our invention relates to coin-controlled vending machines and has for its object the provision of mechanism for automatically 15 testing the deposited coins in several particulars.

One function of our coin-testing mechanism is to prevent iron slugs from operating the machine. Another function is to arrest 20 the passage of rings or washers into operative position within the machine, and the third function of the mechanism is to test the deposited check as to thickness.

The coin-testing mechanism of our invention is so compact in arrangement of parts 25 as to occupy but very little space, so that our invention is particularly applicable to vending machines used in theaters. As is well known, these theater vending machines 30 must be of the smallest possible dimensions, so as not to constitute an obstruction when fastened to the back of the theater chairs. As far as we are aware, machines of this type have heretofore not been protected by 35 coin-testing mechanisms having one or more of the functions above referred to, for the reason that the coin-testing mechanisms of the prior art are too elaborate in their construction and operation to admit of application 40 to a vending machine of essentially small dimensions—such as a theater machine. As a result, the operation of these machines has in many instances been rendered unprofitable, and in some cases they 45 have been operated at a loss, due principally to the use of iron slugs, which opened the machine as readily as a genuine coin.

The foregoing difficulties are entirely obviated by the use of our new coin-testing mechanism which automatically locks the 50 machine against operation through other than a genuine coin, at the same time permitting spurious checks to be withdrawn from the machine to clear the coin-slot.

Considered broadly in one of its aspects, 55 our invention comprises the combination of a coin-controlled locking member and a magnetically controlled device for automatically locking said member against operation when a check of magnetic material 60 is deposited. The precise function of this locking member is immaterial as far as the basic principle of our invention is concerned. In the illustration shown in the drawings, this locking member controls the 65 slide or bolt which locks the lid of the machine.

Viewed in another aspect, the magnetic feature of our invention comprises broadly a movable coin-carrier for conveying the deposited coin into operative position, and means for automatically locking the carrier against complete operative movement, when a check of magnetic material is deposited. The carrier is readily operable to 70 initial position to carry the spurious check back to the coin-opening whence it may be withdrawn by hand.

Another feature of our invention consists in positively arresting the operation 80 of the coin-carrier when a ring or washer is deposited. This is accomplished by means of a yieldably mounted pawl which is projected into the opening of the ring or washer on the carrier and thereby acts as 85 a stop against further movement of the same. The coin-carrier is so constructed that when it comes into engagement with the pawl it automatically represses the same, and is not therefore interfered with 90 when operated in either direction without a coin. When a coin is in the carrier the pawl is held back in its inoperative position by both the carrier and the coin, and the

machine operates as though the washer-catching pawl were not present. This free operation of the coin-carrier in either direction when empty or when carrying a good coin is an important feature of our invention.

Another object of our invention consists in providing means for testing the coin as to thickness. This is accomplished by a recess or cutaway portion in the projection of the locking member which extends into the path of the coin on the carrier. Unless the coin be of the requisite thickness, it will enter the recess on the projection of the locking member without operating the same.

While the purpose of our invention may be mechanically carried out in various ways, we have shown in the accompanying drawings a machine provided with our new coin-testing mechanism in the form now best known to us.

In these drawings Figure 1, is a front view of the machine with parts broken away for greater clearness. Fig. 2, is a rear view of the casing carrying the coin-operated lock and the coin-testing mechanism of the machine, certain parts being broken away for the sake of clearness. Fig. 3, is a plan view of the machine with one of the lids in open position. Fig. 4, is a vertical section through the casing of the machine on line 4—4 of Fig. 1. Fig. 5, is a vertical section on line 5—5 of Fig. 1. Fig. 6, is a vertical section through the front or supplemental casing of the machine which carries the coin-controlled and coin-testing mechanisms. Fig. 7, is a horizontal view in cross-section on line 7—7 of Fig. 2. Fig. 8, is a detached face view of my new coin-carrier. Fig. 9, is an edge view of the same; and Fig. 10, is a fragmentary view in transverse cross-section on line 10—10 of Fig. 2.

To the front wall of the main casing A, which may be of any suitable construction, is attached the supplemental casing B which carries the coin-controlled lock of the machine as well as the coin-testing mechanism of our invention. In the specific instance shown for the sake of illustration, the main casing A is divided by a central partition 1 into two compartments, indicated by 2 and 3. These compartments are provided with lids or covers 4 and 5, respectively, which are hinged at the top of the main casing by means of a rod 6. When in closed position, the lids are flush with the top of the casing. At their under side the lids are provided with a spaced flange 7 having a slot 8 therein for co-operation with a locking member, as will be presently explained.

The supplemental casing B is very shallow as compared with the main casing, and therefore adds but little width to the machine when attached in place. This supplemental casing comprises a casting 9, a

back plate 10 and a front or cover plate 11. Between the plate 10 and the front wall of the main casing A is interposed a spacing plate 12 for accommodating certain parts, as hereinafter explained. The supplemental casing B is secured to the main casing by bolts or screws 13 passing through openings 14 into the main casing. Preferably, the front wall of the main casing is provided with a reinforcing plate 15 for receiving the fastening devices.

The casting 9 is at the back formed with a recess or cutaway portion forming the two coin-entrance slots 15 and 16, a central chamber 17, and a common coin-exit slot 18 open at the bottom. In the chamber 17 operates the rotatable coin-carrier 19 which is in the form of a disk having a pair of oppositely arranged coin-receiving portions 20, as best shown in Fig. 8. The coin-carrier 19 is operatively connected with the knob or wheel 21 at the front of the machine in any suitable manner. In the drawings I have shown the coin-carrier provided with a rectangular slot 22 into which passes the rear end of the stub shaft 23 extending from the knob 21. A screw 24 or other fastening device secures the coin-carrier to the stub shaft 23. By simply removing the screw 24, the coin-carrier and the knob may be readily separated. The stub shaft 23 passes through an opening in the hub or bearing portion 25 formed in the main plate of the casting 9, as best shown in Figs. 5 and 7.

On a stud 26 arranged centrally on the rear side of the casting 9 is pivoted a lever 27 provided at its lower end with a forwardly extending lug 28 which lies in the plane of operation of the coin-carrier, as best shown in Fig. 5. The lug 28 passes through an arc-shaped opening or slot 29 in the rear plate 10. The upper end of the lever 27 is arranged to operate between a pair of lid-locking slides or bolts 30 and 31, which are slidably mounted on the plate 10 by means of pins or studs 32 engaging in the slots 33 formed in the slides. This is best shown in Fig. 2. Each of the lid-locking slides is provided with a rearwardly extending lug 34 and forwardly extending lug 35. The lever 27 and the slides 30 and 31 operate in the opening or chamber 36 formed in the intermediate spacing plate 12. The rearwardly extending lugs 34 extend through aligned openings in the front wall of the main casing and the reinforcing plate 15 into engagement with the flanges 7 on the lids 4 and 5, as clearly shown in Fig. 4. When the slides 30 and 31 are in their normal or unoperated position, the lug 34 of each slide engages the flange 7 of the associated lid and holds the same locked. In Fig. 2 the slide 30 is shown in normal position. However, when one or the other of

the slides is operated into releasing position, as will presently be explained, the lug 34 comes into alignment with the slot 8 in the flange 7 of the lid, and thereby causes the same to be thrown open by the spring-pressed package in the magazine. Fig. 2 shows the slide 31 in operated or releasing position.

With each of the locking slides 30 and 31, is associated a locking member 37 and 38, respectively, which is slidably mounted in the chamber or recess 17 of the casting 9. Each of these locking members is at its upper end provided with a rearwardly extending lug 39, which extends through a vertical slot 40 in the plate 10 into engagement with the projection 41 of the associated slide when the locking member is in normal or uppermost position. The locking members 37 and 38 are normally held in uppermost or locking position by springs 42, which bear at their upper end against the top of the slots 43 formed in the locking members, and at their lower ends against the lugs 44 projecting rearwardly from the casting 9. It should be noted that the locking members 37 and 38 are arranged in the plane of operation of the coin-carrier, and therefore in the plane of movement of the coin on the carrier. Each of the locking members has a lateral extension 45 arranged to project into the path of movement of the deposited coin. The projection 45 of each locking member has a beveled coin-engaging surface 46.

The operation of the coin-controlled locking mechanism as thus far described will now be understood and may be stated as follows: Let us say that the purchaser desires the package of goods in compartment 2, which is the left-hand compartment. He deposits the required coin—as a nickel—into the coin-slot 16, and turns the knob 21 to the left. No matter in what position the coin-carrier may be when the coin is deposited, rotation of the carrier will bring one of the coin recesses 20 into position to receive the deposited coin, which is held in operative position between the coin-carrier and curved wall 47 of the coin-slot. As the coin-carrier is rotated, the deposited coin is carried along the wall 47 until it strikes the coin-engaging surface 46 of the projection 45 on the locking member 38. Further movement of the coin-carrier causes the coin 55 to depress the locking member into releasing position, as shown in Fig. 2, where the coin is indicated at C. The first effect of the coin, therefore, is to draw the locking lug 39 of the member 38 out of engagement with the lid-locking slide 31. Continued rotation of the coin-carrier brings the coin into engagement with the lug 28 at the lower end of the operating lever 27 and rocks the upper end of the lever against the slide 31, which is thereby shifted into releasing posi-

tion. This operated position is shown at the right of Fig. 2. As previously explained, when the slide is in operated position, the lug 34 is in alignment with the slot 8 of the associated lid and unlocks the same. It is 70 usual to provide a spring in the bottom of each chamber in machines of this class, so that as soon as the lid is released, the spring thrusts the package upwardly and thereby 75 opens the lid. This being a common expedient, it has not been thought necessary to show it. Should the purchaser desire a package from the right hand compartment, he deposits the coin in the slot 15, and turns the knob toward the right. This causes 80 the coin to unlock and operate the slide 30 in the manner above described.

After the coin C has actuated the lever 27, further movement of the coin-carrier forces the coin from between the lug 28 and the 85 projection 45 of the associated locking member, and allows the same to drop into the coin-exit slot 18, where it is retained by the bar or bolt 48, to release the coin. The bolt 48 is withdrawn by means of a key inserted 90 in the slot 49 formed in one side of the casting 9. This key is adapted to actuate the tumblers 50 of the lock 51. As the lock 51 forms no part of our present invention, we have not deemed it necessary to show or 95 describe any specific form of lock and key for withdrawing the bolt 48.

As previously stated, the lid-locking slides 30 and 31 are at their adjacent upper ends provided each with a forwardly extending lug 35, which projects through the horizontal slot 52 in the plate 10. The arrangement of the lugs 35 is such that when a slide is in normal or locking position, its lug 35 does not interfere with the passage of the 100 coin through the associated coin slot. This is clearly shown at the left of Fig. 2. However, when the slide is in actuated or releasing position, its lug 35 projects into the associated coin-slot, so as to positively prevent 105 the insertion of a coin into that slot. In Fig. 2, the lug 35 of the slide 31 is shown in slot-closing position. It will thus be seen that when a compartment is empty no coin can be 110 inserted into the corresponding coin-slot, whereby a careless customer is prevented 115 from losing his coin. The slides 30 and 31 are passive—that is to say they are not spring-controlled and remain in their operated position. It therefore becomes necessary to restore them to their initial or locking position. This is done by means of a special key adapted to be inserted into the key-slots 53 formed in the sides of the casting 9 near the upper end thereof. One of 120 these slots is shown at the left of Fig. 2. The other slot is concealed by the plate 10. Each of the slides 30 and 31 is at its outer edge provided with a forwardly extending 125 lug 54 which projects through the horizontal 130 lug 54 which projects through the horizontal

slot 55 in the plate 10, as clearly shown at the right of Fig. 2. The lugs 54 extend into the key slots 53, so that the inserted key engages the lugs and forces the slides inwardly 5 into normal position.

When, during the rotation of the coin-carrier, the coin is forced out of engagement with the associated locking member 37 or 38 after the corresponding slide has been 10 moved into releasing position, said member is at once carried upwardly by the spring 42, so that the locking lug 39 engages the inner shoulder 41^a of the extension 41 of the slide. This locks the slide against re- 15 turn movement and consequently prevents relocking of the empty compartment by an unauthorized person. It is therefore necessary, before the actuated slides can be restored, to depress the locking members 37 20 and 38 out of engagement with the exten- 25 sions 41. This is done by means of the bars 56 which are slidably arranged in the recesses 57 extending downwardly from the key slots 49. Each of the bars 56 is at its lower end provided with an inwardly ex- 30 tends lug 58 adapted to engage the lateral lug 59 on the associated locking member 37 or 38. Only one of the bars 56 is shown entirely in Fig. 2. The bar at the right is 35 partly concealed by the plate 10. Normally, the bars 56 rest by gravity at the bottom of the recess 57, as shown at the right of Fig. 2. When the locking member 37 or 38 is moved into elevated position, as shown at 40 the left of Fig. 2, the lug 59 carries the as- 45 sociated bar 56 upwardly, so that the bevelled outer end 60 of the bar 56 extends into the key slot 53. When, therefore, the key is inserted into this slot, the bar 56 is first 50 depressed to move the associated locking member into releasing position, and as the key is pushed inwardly it comes into contact with the lug 54 of the lid-locking slide and forces the same inwardly into normal position. It is, of course, understood that this 55 restoring of the slides 30 and 31 does not take place until after the attendant has replenished the machine, and while he holds the lids down in closed position.

The foregoing construction of coin-operated lock does not in and of itself constitute a part of our invention, as that construction is the subject matter of the pending application, Serial No. 718,220, filed September 3, 1912 by Samuel J. Kelly and John A. Webster as their joint invention.

We have illustrated our invention as applied to a coin-controlled lock of the foregoing construction merely for the sake of illustration, and not by way of limitation of our invention.

In applying our invention to the coin-controlled lock as above set forth, the object is to prevent the operation of the members 65 37 and 38 into releasing position, when a

check of magnetic material, or a washer, or a check of less than the prescribed diameter or thickness, is deposited in the machine.

We will now take up in detail these dif- 70 ferent functions of our new coin-testing mechanism. In the recess or chamber 61 at the front of the casting 9, is pivoted a pair of supports 62 and 63 on studs or pins 64. These supports carry the magnets 65 and 66, respectively. These magnets are rigidly 75 mounted on their supports in any suitable manner—as by means of lugs 67 struck up from the supports which are preferably con- 80 structed of sheet metal. The poles of the magnets project through openings 68 in the casting 9. These openings are sufficiently 85 large to permit movement of the magnets, as hereinafter described. The outer or free ends of the poles of the magnets lie substan- 90 tially flush with the inner wall of the cham- 95 ber 17 through which the coin is conveyed by the coin-carrier. Fig. 7, shows clearly the termination of the magnet poles in line with the inner wall of the recess 17. By virtue of this arrangement, the deposited 100 check is moved past the poles of one or the other magnet, and comes substantially in contact therewith. Each of the magnet sup- 105 ports 62 and 63 is at its lower end provided with a rearwardly extending lug 69, which 110 projects through the opening 70 in the casting 9 into the path of movement of the as- 115 sociated locking member 37 or 38. Each of these members is at its lower end provided with a slot 70^a, adapted to receive the lug 100 69 when the latter is in operated position, and thereby lock the said member against 115 downward movement into releasing position.

The operation of the magnetic tester of 105 our new coin-testing mechanism is as fol- 110 lows: Let us say that an iron slug is depos- 115 ited in the coin-slot 15 and the coin-carrier turned counter-clock-wise (as viewed in Fig. 2). As soon as the slug comes opposite the 115 poles of the associated magnet 66, the mag- 120 netic attraction causes the magnet to adhere to the slug, and as the latter is swung to- 125 ward the left (as viewed in Fig. 2) by the coin-carrier, the magnet and the support on 130 which it is mounted are also swung slightly to the left, with the result that the locking lug 69 at the lower end of the support 63 is brought into alinement with the slot 70^a on the locking member 37. This movement of the lug 69 into locking position takes place before the slug has forced the member 37 past the lug 69. To prevent any possible failure of this interlocking between the lugs 69 and the locking members 37 and 38, we 125 have beveled the engaging surfaces of the lugs 69 and the locking members, as clearly shown in Fig. 2, so that only a very slight movement of the locking lugs toward the members 37 and 38 is required to enable the 130

oppositely beveled edges of the locking members to cam lugs 69 into the slots 70. By this arrangement the interlocking of the lugs 69 with the members 37 and 38 is rendered certain, no matter how quickly the slug may be carried past the magnets. The slight downward movement of the locking members before they are locked by the lugs 69 is not sufficient to cause unlocking of the 10 slides 30 and 31. The engagement of the lugs 69 with the locking members 37 and 38 positively prevents further operation of the coin-carrier, but it does not interfere with the return movement of the carrier to bring the slug back into the coin-entrance opening for removal by hand. This free operation 15 of the coin-carrier in the reverse direction is essential, otherwise the machine would become clogged after the insertion of the first 20 slug. The casting 9 is preferably recessed opposite each coin-slot, as shown in Figs. 1 and 3, to allow the slug to be more readily grasped by the fingers. The supports 62 and 63 hang by gravity in such a position 25 that the lugs 69 are out of the path of movement of the members 37 and 38, as clearly shown in Fig. 2. Consequently, when a proper coin is deposited, the operation of 30 the members 37 and 38 into releasing position is not interfered with by the lugs 69.

In order to insure the proper operation of the magnets, we prefer to employ means for forcing the deposited check against the magnetic poles. In the drawings, we have 35 shown a spring blade 72 associated with each pair of magnet poles, and so arranged as to project into the recess 17. These spring blades may conveniently be cut out of the plate 10. The upper ends of the spring 40 blades 72 are beveled so that the deposited check may be forced past them. These springs yieldingly press the coin or check against the inner wall of the recess 17, and therefore against the poles of the magnets.

45 In this way there is no chance of any air gap between the magnet poles and the iron slugs, which would weaken the attractive force of the magnet and render its operation uncertain.

50 It will be seen from the foregoing that we have provided an exceedingly simple and efficient means for automatically locking the coin-controlled mechanism against operation when a magnetic slug is deposited in the 55 machine. Of course, it should be understood that the precise arrangement of magnets as herein shown, has been selected merely for the purpose of illustrating our invention, which is applicable by those skilled in the art to coin-controlled mechanisms of various constructions.

We will now describe the means for automatically locking the coin-carrier against full operative movement when a check with 60 an opening—such as a washer or ring—is

deposited. The casting 9 is on the front side provided with a pair of lugs 73 which serve to pivotally support the pawls 74 and 75. The upper free ends 76 of these pawls project rearwardly through slots 77 in the 70 casting 9. A spring blade 78 is secured at an intermediate point to the casting in any suitable manner, as by a screw 79 (see Fig. 5), and is adapted to bear at its ends against the pawls 74 and 75 to force the same rearwardly. It will be observed that the pawl 74 is nearer to the axis of rotation of the coin-carrier than the pawl 75. The reason for this is to allow free rotation of the coin-carrier in either direction by repressing the 80 pawls through the medium of oppositely arranged inclined surfaces on the front face of the coin-carrier. These inclined surfaces are best shown in Figs. 8 and 9. There are two sets of these surfaces—an outer set numbered 85 80, 81, 82, and 83, and an inner set numbered 84, 85, 86, and 87. The outer set of inclined surfaces is adapted to engage the outer pawl 75, while the inner surfaces are arranged to engage the inner pawl 74. The diametrically opposite outer surfaces 80 and 82, and the diametrically opposite inner surfaces 85 and 87, are beveled outwardly from the edge 90 of the coin-carrier. This is indicated by the shading in Fig. 8, and by the dotted 95 lines representing surface 87 in Fig. 9. The diametrically opposite outer surfaces 81 and 83, and the diametrically opposite inner surfaces 84 and 86, incline outwardly from the coin-carrier and terminate each in a lug 88. 100 It will be noted that the two sets of inclined surfaces are beveled reversely with respect to each other, whereby the inner set of surfaces serve to repress the pawl 74 when the coin-carrier is rotated in one direction, while 105 the outer set of surfaces represses the pawl 75 when the coin-carrier is rotated in the opposite direction. We can perhaps best follow the action of the inclined surfaces on their respective pawls by reference to Fig. 8. 110 If we imagine the coin-carrier rotated counterclockwise, it will be clear that the outer set of surfaces approaches the outer pawl 75 from below—that is to say, in the direction 115 of the beveled under-surface 89 on the head of the pawl. Therefore, the projections 88 of the surfaces 81 and 83 repress the pawl 75 forwardly. The inner inclined surfaces 85 and 87 approach the pawl 74 head-on, and cause it to ride over the same. When the direction of rotation of the coin-carrier is reversed, (that is to say, clockwise as viewed in Figs. 1 and 8), the inner set of surfaces approaches the pawl 74 from below, so that the inner projections 88 force this pawl out of their path of movement, while the outer set of surfaces approaches the outer pawl 75 head-on and causes the same to ride over the inclined surfaces 80 and 82. In this way it will be clear that the pawls 74 and 75

do not interfere with the rotation of the coin-carrier in either direction, whether it is empty or whether it carries a coin. However, when the deposited check is a washer 5 or a ring, one or the other of the two pawls will snap into the opening of the washer or ring as soon as the same comes into alignment with the head of the pawl, whereby further rotation of the coin-carrier is prevented.

- 10 The preliminary movement of the coin-carrier before it is thus locked by the pawl, is not sufficient to move the locking member 37 or 38 into releasing position. Furthermore, when the pawl interlocks with 15 the washer, the position of the washer is such that the coin-carrier is free to be rotated in the reverse direction to carry the washer back into the coin-slot and project the same out of the slot sufficiently to permit 20 its removal by hand. If the machine has only one goods compartment, it is of course obvious that only one washer-catching pawl is required, in which event the coin-carrier need have but one set of inclined surfaces.

- 25 It will be seen that our new form of washer-testing device is very simple in construction and at the same time effective in operation. As the pawls are housed within the recess or chamber 61, their presence does 30 not add to the dimensions of the machine.

To prevent the locking members 37 and 38 from being operated by a thin disk, we provide a recess or cutaway portion 90 on the front side of the extension. The springs 72 35 will force the check in the direction of the recesses 90, so that should the check be of less thickness than the width of the recess 90, it will pass through said recess without actuating the associated locking member 37 or 38.

Owing to an official requirement for division, the washer-catching feature of our invention has been divided out of this case and forms the subject-matter of a separate 45 application Ser. No. 58,544, filed Oct. 29, 1915.

Having thus described our invention what we claim as new and desire to secure by Letters Patent of the United States is:

- 50 1. In a coin-controlled vending machine, the combination with a movable member adapted to be operated through the medium of the deposited coin, and a manually operable device separate from said member and movable independently thereof to carry the deposited coin into position to cause operation of said member, of means for automatically locking said member against operation when a check of magnetic material is deposited.

- 60 2. In a coin-controlled vending machine, the combination with a movable member adapted to be operated through the medium of the deposited coin, and a manually operable device separate from said member and

movable independently thereof to carry the deposited coin into position to cause operation of said member of a movable support carrying a magnet, and a stop on said support arranged to be projected into the path of movement of said member to lock the same against operation when a check of magnetic material is deposited.

3. In a coin-controlled vending machine, the combination with a movable member adapted to be operated through the medium of the deposited coin, and a manually operable device separate from said member and movable independently thereof to carry the deposited coin into position to cause operation of said member, of a movably mounted magnet, and a stop so controlled by said magnet as to be projected into the path of movement of said member to lock the same against operation when a check of magnetic material is deposited.

4. In a coin-controlled vending machine, the combination of a coin-chute for receiving the deposited coin, said coin-chute being provided with a chamber between the receiving and discharging ends thereof, hand-operated means movably mounted within said chamber for carrying the coin from the receiving to the discharging portion of said coin-chute, a movably mounted magnet having its poles substantially flush with one wall of said coin-chute and so arranged that the coin is carried past said poles in close proximity thereto, and means controlled by said magnet for automatically locking said coin-carrying means against operation when a check of magnetic material is deposited.

5. In a coin-controlled lock, the combination of a coin-controlled member, a rotatable disk separate from said member and adapted to carry the deposited coin into engagement with said member to operate the same, hand-operable means for rotating said disk, and a magnetically controlled device for automatically locking said member against operation when a check of magnetic material is deposited.

6. In a coin-controlled vending machine, the combination of a rotatable coin-carrier for conveying the deposited coin into operative position, and means for automatically locking said carrier against rotation when a check of magnetic material is deposited, said carrier being rotatable in the reverse direction to permit removal of the deposited check.

7. In a coin-controlled vending machine, the combination of a movable member adapted to be operated through the medium of the deposited coin, a movable support carrying a magnet, a stop on said support arranged to be projected into the path of movement of said member to lock the same against operation when a check of magnetic material is deposited.

magnetic material is deposited, and means for yieldably forcing the deposited check against the poles of the magnet to insure the operation thereof.

5. 8. In a coin-controlled vending machine, the combination of a coin-chute for receiving the deposited coin, hand-operated means for carrying the coin from the receiving to the discharging portion of said coin-chute, a movably mounted magnet having its poles substantially flush with one wall of said coin-chute and so arranged that the coin is carried past said poles in close proximity thereto, means controlled by said magnet for automatically locking said coin-carrying means against operation when a check of magnetic material is deposited, and means for yieldably forcing the deposited check against the poles of the magnet to insure the operation thereof.

9. In a coin-controlled vending machine, the combination of a casing having a compartment, a lid for said compartment, locking mechanism for said lid, means for operating said mechanism through the medium of the deposited coin to release the lid, and means for automatically locking said mechanism against operation when the deposited check is of magnetic material.

30. 10. In a coin-controlled vending machine, the combination of a casing having a compartment, a lid for said compartment, locking mechanism for said lid, means for operating said mechanism through the medium of the deposited coin to release the lid, a movably mounted magnet having its poles so arranged that a deposited check of magnetic material causes said magnet to move bodily, and a stop connected with said magnet for automatically locking said mechanism against operation when the magnet is moved under the magnetic attraction of said check.

45. 11. In a coin-controlled vending machine, the combination of a casing having a compartment, a lid for said compartment, locking mechanism for said lid, means for operating said mechanism through the medium of the deposited coin to release the lid, a pivoted support having a stop which normally does not interfere with the operation of said mechanism, and a magnet carried by said support so that a deposited check of magnetic material rocks said magnet and support and thereby moves said stop into position to lock said mechanism against operation.

55. 12. In a coin-controlled vending machine, the combination of a casing having a compartment, a lid for said compartment, a locking member for said lid, a vertically slid bolt for normally locking said member against operation, means for actuating said member when released, a coin-carrier adapted to carry the deposited coin into op-

erative position, first to move said bolt into releasing position and then to operate said actuating means, a movable magnet adapted to be moved from its normal position when a check of magnetic material is carried by 70 said coin-carrier, and a stop connected with said magnet for locking said bolt against movement when the magnet is in operated position, said carrier being reversely movable to initial position to permit the withdrawal of the magnetic check.

13. In a coin-controlled vending machine, the combination with a slidable locking member adapted to be operated through the medium of the deposited coin, of a 80 swinging magnet adapted to be moved from its normal position by a deposited check of magnetic material, said member and said magnet being mounted to move in substantially parallel planes, and a stop connected 85 with said magnet for locking said member against operation when the magnet is in moved position.

14. In a coin-controlled vending machine, the combination of a casing having a compartment, a lid for said compartment, locking mechanism for said lid, means for operating said mechanism through the medium of the deposited coin to release the lid, a movably mounted magnet having its poles 95 so arranged that a deposited check of magnetic material causes said magnet to move bodily, a stop connected with said magnet for automatically locking said mechanism against operation when the magnet is moved 100 under the magnetic attraction of said check, and means for yieldably forcing the deposited check against the poles of the magnet to insure the operation thereof.

15. In a coin-controlled vending machine, the combination of a slidable locking member adapted to be operated through the medium of the deposited coin, a swinging magnet adapted to be moved from its normal 110 position by a deposited check of magnetic material, a stop connected with said magnet for locking said member against operation when the magnet is in moved position, and means for yieldably forcing the deposited 115 check against the poles of the magnet to insure the operation thereof.

16. In a coin-controlled vending machine, the combination of a main casing having a compartment and a lid therefor, a supplemental casing removably secured to the front of said main casing, coin-controlled locking mechanism for said lid mounted in said supplemental casing, and a magnetically controlled device arranged within said supplemental casing for automatically locking said mechanism against operation when a check of magnetic material is deposited.

17. In a coin-controlled lock, the combination with a coin-controlled member, and a separate hand-operable element adapted to 130

carry the deposited coin into engagement with said member to operate the same, of a magnetically controlled device for automatically locking said member against operation when a check of magnetic material is deposited.

5 In witness whereof, we have hereunto

subscribed our names this ninth day of April, 1913.

ALBERT D. GROVER.
EARL E. BARBER.

Witnesses:

JOSEPH KATZ,
CLAUDE RAND.
